UNITED STATES PATENT OFFICE.

JOSEPH W. WALKER, OF TOPEKA, KANSAS.

LIQUID-FUEL GAUGE.

Application filed February 12, 1925. Serial No. 8,782.

This application is a continuation in part of my pending U. S. application, Serial No. 749,720, filed November 13, 1924.

My invention relates to improvements in liquid level gauges for use in connection with tanks, and the invention further relates to devices of this character which are intended to operate either a visual or an audible signal, when the liquid in the tank reaches a predetermined low level. The invention is intended primarily for use in connection with the fuel tanks of automobiles, motorboats and the like, but obviously is not restricted to such use.

One object of the invention is to provide a device which is rather simple and inexpensive, may be easily installed, and will be highly efficient for the purpose intended.

In the provision of the device, a float-guiding structure is provided for disposition within a tank, a contact-mounting base is provided to engage the upper side of the tank top, stationary contact means are carried by this base, and a movable contact is co-operable with said stationary contact means, said movable contact being controlled by an operating member connected with a float which is slidable along the float-guiding means.

Another object of the invention is to provide unique means for holding the tank, the float-guiding means and the contact-mounting base in assembled relation with each other and for preventing any relative turning thereof about a vertical axis, the means for preventing such turning also forming a guide for the operating member of the movable contact.

A further object of the invention is to make unique provision whereby the float will not be subjected to the wash of the gasoline, in such a manner as to cause continual bobbing of said float, which would often cause it to close the signalling switch, even though a large quantity of gasoline remained in the tank.

Yet another aim is to provide an enclosed switch of such a construction that volatile gases cannot collect in the casing and hence cause fire, even should the switch contacts arc to some extent.

With the foregoing and minor objects in view, the invention resides in the novel subject matter hereinafter described and

claimed, the description being supplemented by the accompanying drawings.

Figure 1 is a vertical sectional view showing the invention applied to a tank and illustrating it in circuit with an electrical alarm.

Figure 2 is a vertical transverse sectional view as indicated by line 2—2 of Fig. 1.

Figure 3 is a horizontal sectional view taken substantially on line 3—3 of Fig. 1.

The drawings above briefly described illustrate what may be considered as the preferred form of construction, but it is to be understood at the outset that while the construction shown has been rather specifically described, numerous variations may be made within the scope of the invention as claimed.

The numeral 1 on the drawing designates a fuel tank having a filling opening 2 which is provided with the usual plug or cap 3. Insertible into the tank 1, through the opening 2, is a float-guiding structure 4 which preferably includes a vertical bar 5 having a laterally turned upper end 6 and a similarly directed lower end 7, the former being adapted to engage the lower surface of the tank top. The lateral end 6 is preferably formed with two openings 8 and 9, a sleeve 10 being threaded or otherwise secured in the opening 8. The reduced upper end 11 of a float-guiding rod 12 passes through the opening 9 and extends above the bar end 6, the lower end of said rod being secured to the lateral lower end 7 of the bar 5, in any suitable manner, as indicated at 13. The sleeve 10 and rod end 11 are adapted for passage through openings formed in the top of the tank 1 and are also intended to pass through similar openings in the common bottom 14 of a pair of spaced contact casings 15, which bottom constitutes a contact-mounting base. A washer 16 is preferably placed around the upper end 11 of the rod 12, in engagement with the bottom of the casings 15, a nut 17 being then threaded on said rod end, so as to clamp the casing, tank, and float-guiding means 4 in assembled relation.

During tightening of the nut 17, the rigid sleeve 10 prevents turning of the float-guiding means 4, within the tank, and said sleeve further acts to prevent any relative turning of the casing bottom 14 and float-guiding means 4, with respect to the tank 1, after the invention is installed.

Contacts 18 are carried by vertical walls

of the two casings 15 and are suitably insulated therefrom, wires 19 and 20 being shown connected with said contacts and constituting part of an electrical circuit for an alarm 5 21 which may be either visual or audible. The circuit is also preferably provided with a manually-opened switch 22, so that when once the circuit is completed, by lowering of the fuel level, the alarm need not operate 10 continually until the fuel supply is replenished. To bridge the gap between the contacts 18 and complete the circuit for the alarm 21, I provide a horizontal contact pin 23 which passes through slots 23^a in the inner sides of the casings 15 and has its ends disposed above said contacts 18. This contact pin 23 is carried by a light vertical rod 24 from which it is appropriately insulated as indicated at 25. This rod 24 passes 15 20 ably through the sleeve 10 and its lower end is suitably connected at 24^b with an appropriate float 26 which is slidable along the rod 12. When there is an amount of liquid in the tank 1, in excess of a predetermined 25 amount, the contact pin 23 is disposed above the stationary contacts 18 and the circuit for the signal 21 is then broken. At this time, the lower end of the sleeve 10 is sealed by an appropriate valve 27 carried by the rod 20 24 so that there can be no leakage of liquid into one of the casings 15. When the liquid level lowers beyond a predetermined extent, the float 26 is allowed to descend so that it brings the contact pin 23 into engagement 30 35 with the contacts 18, completing the circuit of the signal 21 and operating the latter to give warning that the liquid level is rather low. When this warning has been given, the switch 22 may be opened and left open 40 until the fuel supply can be replenished. As soon as more fuel is poured into the tank, the float 26 again rises, moving the contact pin 23 out of engagement with the contacts 18, so that the switch 22 may again be closed 45 to place the device in readiness for further operation.

As there may be liability of some slight arcing between the fixed and movable contacts, it is advisable to provide a construction in which no volatile gases which might possibly escape from the gas tank, can collect in the switch encasing means. Hence, I have provided the two spaced casings 15 which are effectively vented by means of the 50 55 slots 23^a. If any gas should enter these casings, it can readily discharge from the same through the slots, so that there will be no danger of explosion, even if slight arcing between the contacts does take place.

I provide novel means to prevent vertical bobbing of the float 26 and consequent make and break of the switch, which is particularly desirable when the invention is used upon the fuel tank of an automobile. In the 60 65 preferred construction, herein shown, a pro-

tecting casing 28 loosely surrounds the float 26 and is provided with openings through which the rod 12 and rod 24 pass loosely. This casing rests upon the lateral end 7 of the bar 5 and it is adapted to receive liquid 70 from the tank, so as to control the float 26. However, the wash of the liquid around the casing 28, will not materially affect the latter and cannot affect the float 26, to cause vertical bobbing of the latter. Thus, as long 75 80 as a predetermined amount of liquid is in the tank, the float is held at its raised position, and as the liquid level lowers, the casing 28 drains gradually through a port 29 in its bottom, to permit descent of said float. 85

It will be seen from the foregoing that the invention is rather simple and inexpensive, that it may be easily installed, simply by drilling two openings in the top of the tank, that simple means are employed for 85 90 securing the several parts in assembled relation with each other, and that the device will be generally advantageous.

As excellent results are obtainable from the details disclosed, they are preferably 95 followed. However, within the scope of the invention as claimed, numerous modifications may of course be made.

I claim:

1. A liquid level gauge comprising a float-guiding structure for disposition in a tank, said structure including a horizontal portion to engage the lower surface of the tank top, a sleeve rising rigidly from said portion, and a rod whose upper end passes through and projects rigidly above said portion in laterally spaced relation with the sleeve; a contact-mounting base adapted to rest on the tank top, said base having openings to receive said sleeve and said upwardly projecting end of said rod when said sleeve and rod end are passed through the tank top, a nut adapted for threading on said rod end into engagement with said base, stationary contact means on said base, a movable contact co-operable with said stationary contact means, an operating member for said movable contact adapted for passage through the aforesaid sleeve, and a float connected to said operating member, said float being slidably associated with the aforesaid rod. 110 115

2. A liquid level gauge comprising a float-guiding structure for disposition in a tank, said float-guiding structure having a relatively non-rotatable upstanding bolt for passage through an opening in the top of the tank, a nut adapted to be threaded on the upper end of said bolt to secure the float-guiding structure to the tank, a tubular projection rising from the float-guiding structure in laterally spaced relation with the bolt, said projection being adapted for passage through another opening in the top of the tank and serving to hold the float-guiding structure against turning while tightening 120 125 130

ing the aforesaid nut, a float slidably associated with said float-guiding structure, and a rod connected to the float and rising therefrom through the aforesaid tubular projection.

3. A liquid level gauge comprising a pair of horizontally spaced casings adapted to be secured upon a gasoline tank, said casings having slots in their inner opposed sides, 10 stationary contacts in and insulated from said casings, a contact-engaging pin passing through the aforesaid slots to bridge the gap between said stationary contacts, an operating and carrying rod for said pin insulated from the latter and adapted to extend to the interior of the tank, and a controlling float for said rod connected to the inner end of the latter.

4. A liquid level gauge comprising a vertical bar having upper and lower horizontally directed ends each of which is formed with an opening, the two openings being vertically alined, the upper bar end being

also formed with another opening spaced outwardly from its first named opening, a vertical float guiding rod secured at its lower end in the first named opening of the lower bar end, the upper end of said rod being reduced and threaded, said threaded rod end passing through the first named opening of 25 the upper bar end and projecting to a point above the latter for passage through a tank top, a nut for engagement with said threaded rod end to hold the upper bar end against the lower side of the tank top, a sleeve secured in said other opening of the upper bar end and projecting upwardly therefrom for passage through the tank top to prevent rotation of other parts when tightening the aforesaid nut, a float slidable along the 30 above mentioned rod, and an indicator operating stem rising from the float through the aforesaid sleeve.

In testimony whereof I have hereunto affixed my signature.

JOSEPH W. WALKER.
